UNITED STATES PATENT OFFICE.

SAMUEL TREINIS, OF NEW YORK, N. Y.

PUNCHING-BAG PLATFORM.

SPECIFICATION forming part of Letters Patent No. 706,866, dated August 12, 1902.

Application filed March 27, 1902. Serial No. 100,251. (No model.)

To all whom it may concern:

Be it known that I, SAMUEL TREINIS, a citizen of the United States, and a resident of the city of New York, borough of Manhattan, in 5 the county and State of New York, have invented a new and Improved Punching-Bag Platform, of which the following is a full, clear, and exact description.

This invention relates to improvements in 10 platforms for suspending punching-bags; and an object is to provide a device of this character that shall be rigid and strong when supported from a wall or the like and so arranged that it may be readily adjusted to take up 15 possible wear in the joints or connections and adapted to fold compactly for storage or transportation.

I will describe a punching-bag platform embodying my invention and then point out the 20 novel features in the appended claims.

Reference is to be had to the accompanying drawings, forming a part of this specification, in which similar characters of reference indicate corresponding parts in all the figures.

25 Figure 1 is a front elevation of a punching-bag platform embodying my invention. Fig. 2 is a side view thereof. Fig. 3 is a perspective view of a bracket member employed, and Fig. 4 is a sectional view of an extension-brace 30 employed.

Referring to the drawings, 1 designates the platform, consisting of any suitable material, and 2 is a supporting-plate designed to be secured to a wall or the like.

35 On the upper side of the platform 1 is a metal frame 3, having in its rear cross-bar 4 sockets for receiving the forward ends of a bracket-arm 5. The said forward ends of the bracket-arms are tapered rearwardly and the 40 side walls are inclined downward and outward to engage with the correspondingly-shaped walls of the sockets. The upper end portions of the bracket-arm 5 are removably engaged in sockets 6, formed on a plate 7, attached to the supporting-plate 2. The sockets 45 6 have inclined walls and the sides of the upper portions of the arm 5 are correspondingly shaped, and on these ends are inwardly-extended lugs 8, which engage on the upper

50 sides of the socket members, as shown. An extension-brace consists of two members 9 10, adjustably held together by means of a

set-bolt 11, provided with a nut 12. The overlapping portions of these members 9 and 10 are corrugated, as shown in Fig. 4, so that the 55 corrugations of one member will engage with the corrugations of the other member, preventing any possible slipping, and to provide for the lengthening or shortening of the brace the member 10, as here shown, is provided 60 with a slot 13, through which the bolt 11 passes. The lower member 10 has pivotal connection 14 with the frame 3, and the upper member 9 has pivotal connection with lugs 15, secured to the supporting-plate 2. 65

The hanger for the punching-bag 16 consists of a rigid or frame-like member 17, secured to the under side of the platform, and a flexible member 18. By this arrangement the bag may have only sufficient swing to 70 strike against the platform—in other words, by the short flexible member 18 the bag is prevented from passing over the upper side of the platform.

The assembling of the parts will be readily 75 understood from the drawings. Should the connections between the frame and the bracket-arm become loose or worn, the brace may be readily adjusted to move the platform and holder in horizontal position. 80

It will be understood that the plate 2 is not an essential feature, as in practice, at least in most instances, the parts shown as connected thereto will be secured directly to a wall, and therefore the plate and a wall are 85 to be considered equivalents.

Having thus described my invention, I claim as new and desire to secure by Letters Patent—

1. A punching-bag platform, a bracket having removable connection therewith, a longitudinally-adjustable brace consisting of two sections having overlapped ends, the overlapping portions being corrugated on their engaging surfaces, and means for securing 95 the sections as adjusted, substantially as specified.

2. A punching-bag platform, a supporting-plate, a bracket-arm having removable connection with the platform and plate, a brace 100 connection between the platform and plate, the said brace consisting of two sections mounted to slide one upon the other, one section being slotted, and a fastening-bolt ex-

tended from the other section through said slot, substantially as specified.

3. A punching-bag platform, a metal frame secured thereon and provided with sockets, a supporting-plate, a socketed member on said supporting-plate, a bracket-arm adapted to engage in said sockets of the plate and platform, and a brace consisting of two members, adjustable one upon the other, one member having pivotal connection with the platform and the other having pivotal connection with the supporting-plate, substantially as specified.

4. A punching-bag platform, a supporting-plate, socket members on the supporting-plate, socket members on the platform, a bracket-

arm having its upper end adapted to engage in the socket members of the plate, lugs on said upper ends for engaging on the upper sides of the socket members, the lower end ²⁰ of said arm being adapted for removable engagement with the sockets on the platform, and an adjustable brace connection between the platform and supporting-plate, substantially as specified.

In testimony whereof I have signed my name to this specification in the presence of two subscribing witnesses.

SAMUEL TREINIS.
